UNITED STATES PATENT OFFICE.

WILLIAM L. MURPHY, OF SAN FRANCISCO, CALIFORNIA, ASSIGNOR TO MURPHY WALL BED COMPANY, OF SAN FRANCISCO, CALIFORNIA, A CORPORATION OF CALIFORNIA.

DISAPPEARING BED.

1,083,025.

Specification of Letters Patent. Patented Dec. 30, 1913.

Application filed October 18, 1913. Serial No. 794,851.

To all whom it may concern:

Be it known that I, WILLIAM L. MURPHY, a citizen of the United States, and a resident of the city and county of San Francisco, 5 State of California, have invented certain new and useful Improvements in Disappearing Beds, of which the following is a specification.

The invention relates to disappearing 10 beds, and particularly to that type of disappearing beds known as wall beds.

The object of the invention is to provide 15 a wall bed construction whereby a bed may be readily moved into and out of a closet of much less width than the width of the bed.

Another object of the invention is to provide 20 a wall bed construction which permits the closet door to be closed when the bed is in the room.

The invention possesses other advantageous 25 features, which, with the foregoing, will be set forth at length in the following description, where I shall outline in full that form of the invention which I have selected 30 for illustration in the drawings accompanying and forming part of the present specification. The novelty of the invention will be included in the claims succeeding said description. From this it will be apparent 35 that I do not limit myself to the showing made by said drawings and description, as I may adopt many variations within the scope of my invention as expressed in said claims.

Referring to said drawings: Figure 1 is a 40 top or plan view of the folded bed in the closet, the dotted lines indicating the position of the bed as it is being swung on its pivot. Fig. 2 is an elevation of one side of the closet, showing the rails and carriage upon which the bed is arranged. Fig. 3 is a fragment in plan view of a modified form 45 of construction which permits of the use of a narrower closet than the former construction. Fig. 4 is a fragment in plan view of a modified form of the construction shown in Fig. 3.

The bed is of the foldable type, movable 50 in a vertical arc from a horizontal to a vertical position and vice versa, and in the drawings is shown in the vertical or folded position. Arranged at one side of the closet 2 and preferably attached to the wall thereof are the rails 3-4 on which the carriage 5 is 55 arranged to move. The carriage is provided

at its upper end with grooved wheels or rollers 6 bearing on rail 3 and at its lower end with grooved wheels or rollers 7 engaging the under side of rail 4. This arrangement prevents a vertical or a tilting movement of 60 the carriage. The carriage is preferably formed of the two vertical members 8-9 to the opposite ends of which the rollers are journaled and the two horizontal members 12-13, the various members being suitably 65 connected and braced.

The bed frame 14 is suitably mounted upon a suitable carrying structure, which may consist of the substantially rectangular frame 16, so that the bed frame may swing 70 in a vertical arc from the horizontal to the vertical position and vice versa. The frame 16 is pivotally attached to the carriage 5 at a point intermediate between the sides of the bed frame and preferably to one side of 75 the center line of the bed. This pivotal mounting is preferably arranged by providing the carriage 5 with forwardly projecting arms 17 which provide bearings for the vertical rod 18 which is secured to the upper 80 and lower rails of the frame 16. When the bed is to be moved from the closet into the room, the carriage 5 is moved forward on the rails 3-4, to move the pivotal point of connection between the bed and the carriage 85 out of the closet and then the bed may be revolved on its pivot to cause the head of the bed to lie substantially parallel with the wall of the room. This construction allows the bed to be moved into and out of a narrow 90 closet.

In the construction illustrated in Fig. 3, I have shown an arrangement whereby a still narrower closet may be used. The arms 17 are made longer so that when the carriage 95 is in its forward position, the rod 18 is spaced considerably from the wall of the room. By thus moving the center of rotation of the bed farther out of the closet, a narrower closet may be used and the door 100 of the closet may be closed when the bed is in the room. After the bed has been turned so that the head thereof lies substantially parallel with the wall of the room, the carriage 105 may be moved backward so that the carrying frame lies against the wall.

In Fig. 4, the arms 17 are pivoted to the carrying frame and to the carriage, so that the bed may be swung to one side of the closet opening when it is in the room. This 110

construction includes all of the advantages of the construction shown in Fig. 3 together with the advantage previously mentioned, and the fact that it may be used in a deep 5 narrow closet or a shallow wider closet. When the closet is narrow the arms 17 will lie substantially parallel with the closet wall, when the bed is in the closet, and when the closet is wide and shallow the bed may be 10 swung so that the arms 17 lie substantially perpendicular to the wall, when the bed is in the closet.

I claim:

1. The combination with a wall having a 15 closet opening therein, of a carriage mounted to move horizontally in said closet, and a carrying frame of greater width than said opening pivotally attached intermediate its sides to said carriage, whereby the carrying 20 frame may swing in a horizontal plane with respect to said carriage.

2. The combination with a wall having a closet opening therein, of rails arranged at 25 one side of said closet, and extending substantially for the depth thereof, a carriage mounted for travel on said rails, and a carrying frame of greater width than said closet opening pivotally attached intermediate its sides to the forward end of said carriage.

3. The combination with a wall having a closet opening therein, of horizontal rails 30 arranged at one side of said closet, a carriage mounted for travel on said rails and a carrying frame of greater width than said 35 closet opening pivotally attached intermediate its sides to the front end of said carriage, said pivotal point being so placed that when the carriage is in its forward position, the pivotal point lies in front of said wall.

4. The combination with a wall having a 40 closet opening therein, of horizontal rails arranged at one side of said closet and ex-

tending substantially for the depth thereof, a carriage mounted for travel on said rails, arms extending forwardly from said carriage, and a carrying frame of greater width than said opening, pivotally attached intermediate its sides to said arms. 45

5. The combination with a wall having a 50 closet opening therein, of horizontal rails arranged at one side of said closet, a carriage mounted for travel on said rails, arms pivotally attached to the forward end of said carriage, and a carrying frame of greater width than said opening pivotally 55 attached intermediate its sides to the other ends of said arms.

6. The combination with a wall having a 60 closet opening therein, of a carriage mounted to move horizontally in said closet, arms pivotally attached to the front end of said carriage by vertical pivots, and a carrying frame of greater width than said opening pivotally attached intermediate its sides to 65 said carriage.

7. The combination with a wall having a 70 closet opening therein, of horizontal rails arranged at one side of said closet and extending substantially for the depth thereof, a carriage, rollers on said carriage engaging on opposite sides of said rails, vertically disposed bearings arranged on said carriage and a carrying frame of greater width than said opening provided with a vertical rod arranged intermediate the sides of said 75 frame, engaging in said bearings.

In testimony whereof, I have hereunto set my hand at San Francisco, California, this 6th day of October, 1913.

WILLIAM L. MURPHY.
